The Schedule referred to in these Letters Patent and making part of the same, containing a description in the words of the said Emanuel Guthrie himself of his improvement in the Manufacture of gunpowder to be used in the discharge of fire arms.

Be it known that Emanuel Guthrie of Gluckels Harbor in the County of Jefferson and State of New York have invented an improvement in the manufacturing of gunpowder for the discharging of fire arms and do hereby declare that the following is a full and exact description thereof.

I prepare the gunpowder from any of the materials employed for that purpose using gunpowder, Mercury, Potassium Nitro and Oxide of tin, or regalia of antimony. I elaborate of Potash with Chalcocite Sulphur, Sulphur of antimony or any mixture of substances capable of inflaming gunpowder by forecussion forming the grains into a paste and granulating by repeated dipping which is done sometimes making the grains of a small size like those of ordinary Gunpowder at other times I make them of such size that a single grain suffices for a priming and I distribute, for the Copper Caps used in loading pieces muskets &c or still larger so that they may be used for the discharge of ordnance of all descriptions. These grains are so compounded that they are hard enough to be packed up and carried about without being liable to be crushed by their attraction against each other only my force to reduce them are necessary. These grains are rendered more perfectly by coating them with shellac dissolved in alcohol or any other resinous varnish. Such powder I have for some time been in the habit of manufacturing and testing but I have recently made the improvement hereinabove which is as follows.

After the varnish dries the grains are coated is perfectly by Glaze or Coat them with some metallic substance, and this I do by taking leaf Pewter or any of the metallic powders known under the name of brass or with Sulphur of tin, or any other Metal or Metallic Compound and in these I

with the grains whilst yet tacky with the varnish. The powder thus prepared is not only improved in appearance but has greater smoothness and durability than before. After thus coating the grains I sometimes apply another coating of Copal, or other varnish, prof. varnish being preferred in this particular by the nature of the powder or ship's paint which it is to be applied. What I claim as my invention and wish to have secured to me by Letters Patent is the giving to the granulated powder a metallic coating in the manner and for the purpose herein set forth.
